US0D1041031S

(12) United States Design Patent (10) Patent No.: US D1,041,031 S
(45) Date of Patent:  Sep. 3, 2024

(54) OUTDOOR STORAGE SHED

(71) Applicant: KETER HOME AND GARDEN PRODUCTS LTD, Herzliya (IL)

(72) Inventors: Avi Askof, Kocav Yair (IL); Shai Azati, Kiryat Tiv'on (IL)

(73) Assignee: KETER HOME AND GARDEN PRODUCTS LTD, Herzliya (IL)

() Term: 15 Years

(21) Appl. No.: 35/514,156

(22) Filed: Feb. 24, 2022

(80) Hague Agreement Data

Int. Filing Date: Feb. 24, 2022

Int. Reg. No.: DM/220289

Int. Reg. Date: Feb. 24, 2022

Int. Reg. Pub. Date: Apr. 29, 2022

(51) LOC (14) Cl. 25-03

(52) U.S. Cl.

USPC D25/33; D6/671.1

Primary Examiner — Brett Miller

(74) Attorney, Agent, or Firm — CANTOR COLBURN LLP

(57) CLAIM

The ornamental design for outdoor storage shed, as shown and described.

DESCRIPTION

3. Outdoor storage shed

3.1 isometric

3.2 Front

3.3 Back

3.4 Left

3.5 Top

3.6 Bottom

The right-side view is omitted because it is a mirror image of the left side; the parts colored in white and delineated with dashed lines illustrate portions which are not part of the claimed design.

1 Claim, 5 Drawing Sheets
